Specification for Design.

Patented Apr. 30, 1912.

Application filed November 5, 1910. Serial No. 590,908. Term of patent 14 years.

To all whom it may concern:

Be it known that I, HERBERT W. SPELLMAN, a citizen of the United States, residing at New Britain, in the county of Hartford and State of Connecticut, have invented a new, original, and ornamental Design for a Stand for Electrically-Driven Machines, of which the following is a specification, reference being had to the accompanying drawing, forming part thereof.

The figure is a perspective view of a stand for an electrically driven machine showing my new design.

I claim:

The ornamental design for a stand for an electrically driven machine, as shown.

HERBERT W. SPELLMAN.
